UNITED STATES PATENT OFFICE.

JOHN E. ERIKSON, OF EDGERTON, ALBERTA, CANADA.

ATTACHMENT FOR GUNS.

1,114,973.

Specification of Letters Patent. Patented Oct. 27, 1914.

Application filed February 13, 1913. Serial No. 748,226.

To all whom it may concern:

Be it known that I, JOHN E. ERIKSON, a subject of the King of Great Britain, residing at Edgerton, in the Province of Alberta, 5 Dominion of Canada, have invented new and useful Improvements in Attachments for Guns, of which the following is a specification.

My invention relates to attachments for 10 guns or firearms, and more specifically to an attachment providing means whereby cartridges may be automatically fed to guns or firearms, and especially shotguns upon the breaking of the stock, to permit the discharge or removal of a cartridge after firing.

The invention aims to provide a highly 15 effective device for the purpose stated; a device employing few, simple and durable parts, providing a construction that can be 20 manufactured at moderate cost.

One embodiment of the invention is described hereinafter in connection with drawings accompanying this application.

In said drawings:—Figure 1 is a plan 25 view illustrating the attachment in connection with a gun barrel and stock, the latter parts being shown fragmentarily; Fig. 2 is a view mostly in section illustrating the attachment in horizontal section, the cartridge 30 deliverer being shown projected, the gun barrel also being shown; Fig. 3 is a view somewhat similar to Fig. 2 but showing the cartridge deliverer within its housing, and also the gun-stock; Fig. 4 is an end view of 35 the attachment showing the cartridge deliverer projected; Fig. 5 is a cross sectional view through the attachment showing the cartridge deliverer housed therein; Fig. 6 is an elevation looking toward the delivery 40 side of the attachment, the parts being shown fragmentarily and the actuating member specifically shown; Fig. 7 is a detail view partly in section of the means employed to control the actuation of the cartridge 45 discharge plate of the deliverer; Fig. 8 is a plan view of the actuating member of the device shown in Fig. 7; and Fig. 9 is a plan view of the control member which cooperates with said actuating member.

Throughout the drawings like reference characters designate like or similar parts.

Referring specifically to the drawings, the attachment is shown in connection with a shotgun of which 1 designates a stock 50 adapted to be broken as usual, from the gun barrel 2 adjacent the magazine 3 thereof.

A casing is provided to house most of the parts of the attachment and thereof 4 designates a cartridge magazine and 5 a housing for a cartridge deliverer presently to be described. The casing is attached to or supported from the gun in a suitable manner, as by means of clamps 6 which surround the magazines 3 and 4. Within the housing 5 is mounted so as to be projected therefrom and into line with the gun barrel at a proper time, by means later to be described, a cartridge deliverer designated 7. When the stock and barrel are in closed relation, the deliverer is in the position best seen in Fig. 3. Cartridges are supplied to the magazine 4 through a door 8 shown in dotted lines in Fig. 1, which door as is obvious, may be of any suitable construction and provided at any suitable location. Within the magazine 4 is mounted a compression spring 9 at one end of which is provided a plate 10. This plate 10 is adapted to bear against the cartridges and through the expansion of spring 9 to supply cartridges to the deliverer when the deliverer is returned to the housing empty. Interior of the magazine 4 is provided a guard member to prevent the supply of a cartridge to housing 5 while the deliverer is in projected position. Such guard 75 consists of a spring leaf 11 having a projection 12 against which the cartridge is adapted to bear. This is best shown in Fig. 2 and the cartridge is shown in said figure in dotted lines, as bearing against said projection.

As stated, the deliverer is adapted to be projected out of and beyond the housing 5 so as to be in alignment with the gun barrel and accordingly in proper position to discharge a cartridge thereto. Such means may be as follows. Extending downwardly from the casing, specifically housing 5, is a lug 13 which has pivoted thereto a control plate or member designated 14. Connected to plate 14 on the horizontal center line thereof, and to the housing 5, is a coil spring 15. To plate 14 is attached a rod or arm 16 which terminates in a yieldable hook portion 17. The hook portion 17 is adapted to cooperate with a lug 18 provided on the housing 5. On the deliverer is provided an eyelet or the like 19 through which the rod 16 loosely passes and has engagement with the deliverer.

Stock 1 has connected thereto as through the medium of a clamp band or member 20.

an actuating rod 21, which rod bears against one face of control face 14 and is also pivoted to the casing referred to, and more specifically the magazine 4, as at 22.

5 Suitable means is provided to limit the extent of projection of the deliverer relatively to housing 5. As shown at the closed end of the deliverer, is provided an arm 23 having a projection 24 which slides in an 10 elongated slot 25 provided in the closed end of housing 5. On deliverer 7 is provided a pin 26 which extends into an elongated slot 27 of a bracket 28. This bracket 28 has pivoted thereto a link 29 which in turn is pivoted to housing 5. Also on the bracket are provided lugs 30, one adjacent each end, which lugs are adapted to coöperate with a lug 31 provided within housing 5. Said lug 31 is preferably provided on an adjustable 15 plate member 32 so that its position may be altered to regulate the extent of projection of bracket 28 and accordingly the extent of projection of deliverer 7; this being desirable, as the various makes of guns differ 20 in size.

Pivoted to a lug 33 provided on one side of the deliverer, is a guard member 34 having a weight 35 at one end which normally maintains the lug in tilted position, as 25 shown in Fig. 2. This lug in such tilted position, projects through an opening in the wall of the deliverer, and into the path of discharge of the cartridge therein. After the discharge of the cartridge from deliverer 7, and return of the deliverer to the housing, guard 34 engages the spring guard 11 and depresses the same so that lug 12 moves out of the path of the abutting cartridge whereupon spring 9 and plate 10 40 move or discharge the cartridge into the deliverer.

Means is provided whereby a cartridge contained in the deliverer will be ejected or discharged therefrom when the deliverer 45 has been projected or moved into alignment with the gun barrel. Such means may be as follows: On the lug 36 within housing 5 is provided a pin 37 which extends through an elongated slot 38 of an arm 39, carried by 50 an actuating member or plate 40 for the control member or plate 41 of the means to discharge a cartridge from deliverer 7. On one side of deliverer 7 is provided any suitable form of bracket such as that designated 55 42. To this bracket, as by means of a pin or bolt 43 are pivoted the actuating member 40 and control member 41. The control member 41 is provided with an arm or projection 44 which extends through an elongated slot 60 45 provided in a wall of the deliverer. Within deliverer 7 is slidably mounted a plate or disk 46 between which and the closed end of the deliverer, is mounted a compression spring 47. Arm or projection 44 is adapted to normally maintain the slid-

able plate 46 in position compressing spring 47, and is also adapted to return the plate to such position after discharge of a cartridge. To permit such action a lug 48 is provided on bracket 42 and adapted to be engaged by 70 a detent 49 pivoted at 50 to control member 41. When the detent 49 engages lug 48 as shown in Fig. 7, disk 46 is maintained by projection 44 in position compressing spring 47. Attached to the detent is a spring 51 75 which also surrounds or is attached to pivot 43. A lug 52 is provided to limit turning or swinging movement of detent 49 in one direction; the spring permitting a limited movement in the other direction. It will be noted that the engagement of detent 49 with lug 48, is slight. To effect disengagement of the detent and lug, a wedge or clamp 53 is provided on actuating member 40, and upon movement of such member to wedge in between the projecting part of detent 49 and the periphery of control member 41 and adjacent the lug 52. This action will move the control member 41 80 backward to a slight extent and permit detent 49 to disengage lug 48. To restore control member 41 to normal position, a lug 54 is provided on actuating member 40 to operate against arm or projection 44. 85

The operation may be summarized as follows: The attachment is secured to the gun by means of the brackets or clamps 6 and 20; it being obvious that said clamps are removable and that their size may vary according to the size of the gun to which the attachment is applied. When the stock 1 and barrel 2 are closed relatively to each other, the deliverer 7 is within housing 5 and maintained therein through the action of spring 15, as best shown in Fig. 5; the specific 100 manner of fastening the spring to the control member 14 enabling the parts to operate to effect retention of deliverer 7 within the housing. Upon breaking of the stock 110 relatively to the barrel, actuating member 21 moves against the control member 14, 115 tilting the same so that the point of connection of the spring 15 therewith will be below the pivot connecting the control member to lug 13, whereupon the spring 15 will 120 actuate the control member 14 and arm 16 to project the deliverer from the housing, the extent of projection being limited by means of the elongated slot 25 and connection of pin 24 therewith, and by means of bracket 125 28 and associated parts. Upon projection of the deliverer to the fullest extent, arm 39 through the connection of pin 37 and elongated slot 38, has been rotated to such an extent that wedge 53 acts against detent 49 disengaging the same from lug 48, whereupon spring 47 and plate 46 act upon the cartridge within the deliverer and discharge the same into the magazine 3 of the barrel. While the cartridge is within the deliverer, 130

accidental movement thereof is prevented by the part of guard 34 projecting into the deliverer. In its movement from the deliverer, the cartridge bears against the inclined face of guard 34 and readily depresses the same from its path. This projecting part also prevents return of the cartridge to the deliverer. After such discharge has been effected, stock 1 is closed relatively to the barrel 2 and through the medium of the various parts deliverer 7 is restored to its normal position within housing 5. During such movement of deliverer 7, lug 54 on actuating member 40 bears against projection 44 and restores the same to normal position or position shown in Fig. 3; spring 51 permitting detent 49 to yield when passing lug 48. Also during such return movement of deliverer 7, the guard 34 bears against the spring guard 11 depressing the same and permitting spring 9 and plate 10 to discharge a fresh cartridge into the deliverer.

The gun is preferably provided with means to eject a shell or cartridge from the barrel after firing. The supply or delivery of a cartridge to magazine 3 occurs subsequent to the ejection of a fired cartridge from magazine 3.

As it might be desirous in some instances to fasten the attachment parts so that the same will not operate upon the breaking of stock 1, relatively to barrel 2, the hook 17 and lug 18 have been provided. When it is desired to render the parts inoperative, the spring hook is moved into engagement with lug 18.

It is to be understood that changes in the details of construction may be made within the spirit and scope of the appended claims, and are accordingly reserved.

Having thus described my said invention, what I claim as new and desire to secure by Letters Patent is:—

1. In combination with a gun having a barrel and a stock breakable relatively to the barrel, a deliverer, a cartridge magazine, means to feed cartridges to said deliverer from said magazine, means to project said deliverer into alignment with said barrel in the space exposed by the stock subsequently to breaking of the stock, and means to discharge cartridges from said deliverer into said barrel.

2. In combination with a gun having a barrel and a stock breakable relatively to the barrel, a deliverer, means to project said deliverer into the space exposed by the stock and retract said deliverer subsequently to breaking of the stock and prior to closing of the stock.

3. In combination with a gun having a barrel and a stock breakable relatively to the barrel, a deliverer, means to move said deliverer intermediate the stock and barrel when in broken relation to position aligning

with said barrel, and means to discharge a cartridge from said deliverer to said barrel prior to firing.

4. In combination with a gun having a barrel and a stock breakable relatively to the barrel, a deliverer to hold cartridges against lateral displacement, and means to move said deliverer into alignment with the barrel through breaking movement of the stock for discharge of the cartridge through movement longitudinally of the deliverer.

5. In combination with a gun having a barrel and a stock breakable relatively thereto, a cartridge deliverer, a casing for said deliverer offset from the gun and means to project said deliverer from the casing into the space exposed by the stock subsequent to breaking of the stock in alignment with the barrel connected to and operable through movement of the stock.

6. In combination with a gun having a barrel and a stock breakable relatively thereto, a cartridge deliverer, a casing for said deliverer offset from the gun and means to project said deliverer from the casing into the space exposed by the stock subsequent to breaking of the stock in alignment with the barrel connected to and operable through movement of the stock, and means to limit the extent of projection of the deliverer from the casing.

7. In combination with a gun having a barrel and a stock breakable relatively thereto, a cartridge deliverer, means to supply cartridges to said deliverer, a casing for said deliverer offset from the gun and means to project said deliverer from the casing into the space exposed by the stock subsequent to breaking of the stock in alignment with the barrel connected to and operable through movement of the stock.

8. In combination with a gun, a movable member, a deliverer, a casing for said deliverer offset from the gun, pivot means to control the projection of said deliverer relatively to the casing connected to said deliverer, an arm secured to said movable member mounted in operative relation to said control means, and a spring for said control means.

9. In combination with a gun having a movable stock, a deliverer, a control member, a spring connected to said member, said member having an arm engaging said deliverer, and a rod mounted in operative relation to said control member movable with said stock to actuate said control member.

10. In combination with a gun, a deliverer, means to project said deliverer, a slideable plate in said deliverer, a spring bearing against said plate, and means to control the movement of said plate.

11. In combination with a gun, a deliverer, means to project said deliverer, discharge means for said deliverer, control

- means for said discharge means comprising a plurality of relatively movable members, one of said members having a projection engaging said discharge means.
- 5 12. In combination with a gun, a deliverer, means to project said deliverer, a discharge plate within said deliverer, a spring bearing against said plate, a plurality of relatively movable members pivoted to said deliverer, one of said members having a projection extending into the deliverer and engaging said plate, a detent for one of said members, and a lug engaged by said detent.
- 10 13. In combination with a gun, a deliverer, means to project said deliverer, a discharge plate within said deliverer, a spring bearing against said plate, a plurality of relatively movable members pivoted to said deliverer, one of said members having a projection extending into the deliverer and engaging said plate, a detent for one of said members, a lug engaged by said detent, the other of said members provided with a detent shifting lug, and a lug to engage said projection.
- 15 14. In combination with a gun, a deliverer, means to project said deliverer, a discharge plate within said deliverer, a spring bearing against said plate, said deliverer provided with an elongated slot and with a bracket, a control member pivoted to said bracket having a projection extending through said plate, a pivoted detent on said control member, a spring fastened to said detent, a lug on said bracket engaged by said detent, an actuating member pivoted to said bracket, said actuating member provided with a wedge lug and with a lug to engage said projection of the control member.
- 20 15. In combination with a gun, a deliverer, means to project said deliverer, a discharge plate within said deliverer, a spring bearing against said plate, said deliverer provided with an elongated slot and with a bracket, a control member pivoted to said bracket having a projection extending through said plate, a pivoted detent on said control member, a spring fastened to said detent, a lug on said bracket engaged by said detent, an actuating member pivoted to said bracket, said actuating member provided with a wedge lug and with a lug to engage said projection of the control member, a pin provided on said actuating member having an elongated slot, in combination with a housing, and a pin provided on said housing extending through said slot.
- 25 16. In combination with a gun, a deliverer, a cartridge magazine, means to discharge a cartridge into said deliverer, and stop means for the cartridge adjacent one end of said magazine comprising a spring having a cartridge-engaging projection, and a pivoted member carried by said deliverer operable against said spring to depress the same.
- 30 17. In combination with a gun, a deliverer, a cartridge magazine, means to discharge a cartridge into said deliverer, yieldable stop means for the cartridge adjacent one end of said magazine, and means carried by said deliverer to actuate said yieldable stop means comprising a pivoted element operable against said stop means, said element provided with means to maintain it in position projecting into the deliverer normally, for the purpose specified.
- 35 18. In combination with a gun, a cartridge magazine, a movable deliverer to receive cartridges from said magazine, means to maintain cartridges within said magazine against discharge into said deliverer, a movable member on said deliverer operable to prevent return of a cartridge thereinto after firing, said member during movement of the deliverer operable against said means to shift the same to permit discharge of a cartridge.
- 40 19. In combination with a gun, a deliverer, a cartridge magazine, means to discharge cartridges from said magazine into said deliverer, a yieldable stop member for the cartridges having a projection forming a stop, said deliverer having a guard pivoted thereto adjacent one end and extending into the cartridge chamber thereof, said guard mounted to engage and actuate said stop member to permit discharge of a cartridge.
- 45 20. In combination with a gun, the movable stock and the barrel thereof, a cartridge magazine, a housing on and offset from said gun, a deliverer within said housing, means to supply cartridges from said magazine to said deliverer, means to project said deliverer from said housing into alignment with the barrel, said means having a part movable with said stock to actuate the projecting means.
- 50 21. In combination with a gun, the movable stock and barrel thereof, a magazine, a housing on and offset from said gun, a deliverer mounted in said housing, means to feed cartridges from said magazine to said deliverer, means to project said deliverer from said housing into alignment with said barrel, said means having a part movable with said stock to actuate the projecting means, means to limit the extent of projection of said deliverer, and means to discharge a cartridge from said deliverer into said barrel.
